(57) **CLAIM**

The ornamental design for a "film sheet for use in antiballistic articles," as shown and described.

DESCRIPTION

FIGS. 1 and 2 are photographic top and bottom plan views, respectively, of a film sheet for use in antiballistic articles which embodies our new and original design therefore, the side views thereof being unornamented.

The broken lines in the drawing represent the bounds of the claimed design and form no part of the claimed design.
